UNITED STATES PATENT OFFICE.

ARTHUR HERMAN ADAMS, OF LA GRANGE, ILLINOIS, ASSIGNOR TO WESTERN ELECTRIC COMPANY, INCORPORATED, OF NEW YORK, N. Y., A CORPORATION OF NEW YORK.

MATERIAL-WINDING MECHANISM.

Application filed October 7, 1924. Serial No. 742,108.

This invention relates to material winding mechanisms, and more particularly to strand feeding and distributing devices.

An object of the invention is to provide an improved material feeding and distributing device for use with material winding machines.

In accordance with the features of the invention there is provided in one embodiment thereof, a composite feeding sheave comprising a disc having a thickness corresponding to the diameter of the strand to be fed, interposed between a pair of knife edge discs of a diameter slightly greater than the intermediate disc, preferably by a distance not greater than the diameter of the strand being fed, the thickness of the sheave at its delivery point being substantially the same as the diameter of the strand. The composite sheave is rotatably mounted upon a distributor arm with its delivery point closely adjacent to the winding surface of a rotating spool, the forward end of the distributor arm being pivotally secured to a member reciprocating in a path parallel to the longitudinal axis of the spool during the winding of each layer thereon. The other end of the arm is tapered and its movement in a horizontal plane is limited only by two spaced stationary stop members so that it may move freely to and from the winding arbor during the reciprocations of the forward end of the arm. At the end of each reciprocation of the composite sheave, which may be built up according to the size of strand being wound, the end turn will be placed snugly against the inner face of the spool flange or at a definite predetermined point on the spool.

It is believed that the invention will be clearly understood from the following description taken in connection with the accompanying drawings illustrating one embodiment of the invention, in which

Fig. 1 is a fragmentary plan view of a coil winding machine equipped with strand feeding and distributing devices embodying the invention;

Fig. 2 is a fragmentary end view looking toward the left of Fig. 1;

Fig. 3 is an enlarged plan view of the de-

vice, showing the position thereof with respect to one head of a spool being wound, at the end of a reciprocatory movement, and

Fig. 4 is an enlarged fragmentary sectional view of the feeding sheave and spool flange shown in Fig. 3.

The driving elements for the spool to be wound and the mechanism for reciprocating the arm, which feeds the strand longitudinally of the spool while it is rotating and for adjusting the lead of the arm, may be identical with those disclosed in my U. S. Patent No. 1,117,620 of November 17, 1914, while the mechanism for maintaining a constant spaced relationship between the feeding sheave and the previously applied layer of strand on the spool may be identical with that disclosed in U. S. Patent No. 1,471,634, to Thronsen et al. of October 23, 1923, but these elements and mechanisms are not herein shown or described as they form no part of the present invention.

In the drawings, 10 represents a rail supported upon the frame of the winding machine indicated at 11, upon which rail is slidably mounted, in a manner similar to that disclosed in the above mentioned Patent No. 1,471,634, a head block 12 having slidably mounted thereon a slide 13. Loosely mounted in a depending portion 14 of the head block 12 by a suitable pin or screw 15 is an arm 16, which is reciprocated by any suitable means (not shown), for instance the means disclosed in my above mentioned patent, in a suitable slot 17 formed in the frame 11 of the winding machine.

The slide 13 projects forwardly of the head block 12 and lies in the same horizontal plane as the top thereof (Fig. 2). A wire feeding arm 21 is pivotally secured at its forward end to the projecting portion of the slide 13 by a pin 22 and rests upon the top surface of the slide 13. The rear of the arm 21 is tapered and is limited in its horizontal movement by two stationary pins 24, one on either side thereof, which pins are secured to a bridge member 25 which may be suitably fixed to the frame of the machine. The pins 24 restrict the movement of the tapered end of the arm in a direction lengthwise of the bridge 25, but permit it

to move freely laterally thereof. Mounted upon the forward end of the feeding arm 21 just behind the pivot pin 22 is a feeding sheave 26 supported by a bracket 27 suitably secured to the feeding arm 21. The sheave 26 is so positioned that the axis of the wire to be fed thereby will be in line with the axis of the pivot pin 22. The feeding sheave comprises two knife edge discs 30 with an interchangeable disc 31 therebetween, having a diameter slightly less than the discs 30 and a thickness corresponding to the diameter of the wire to be wound. For accurate spooling of wire, particularly for winding electrical coils, it is essential that the guiding surface of the feeding sheave corresponds to the diameter of the wire being wound so that the end turns of the wire being wound can be snugly placed against the inner sides of the heads or flanges of the spool. It will readily be seen that by providing a sheave wherein the peripheral guide surface may be changed to provide a surface of a width equal to the diameter of the wire being wound, the wire will be placed close to the inner sides of the flanges of the spool. This results in preventing any pockets or ridges being formed during the winding operation, which would occur if a guide surface designed for a large wire were used for a smaller diameter wire, since the wire would move over to the inside face of the flange of the sheave in a direction opposite to that which the feeding arm 21 was moving, thereby preventing the end turn of wire from being placed snugly against the flange of the spool.

In operation the head block 12 is moved first toward one flange of the spool and then toward the other by the reciprocating arm 16, and at the end of each movement toward either flange 32 of the spool 33 the slide 13 is stepped backwardly, a distance equal to the diameter of the wire being wound. During the sidewise movement of the head block 12, the forward end of the arm 21 carrying a sheave built up according to the diameter of the wire being wound, through its pivot connection 22 with the slide 13, is carried along therewith, the opposite end being held from movement longitudinally of the spool by the stationary pins 24, but sliding forwardly and backwardly successively, thus pivoting at a plurality of points located lengthwise of the arm. These latter movements are necessary due to the varying distance between the axis of the sheave and the stationary pins 24 during operation, as is indicated by the dotted position of the feeding arm 21 (Fig. 1). As indicated clearly in Figs. 3 and 4, the outside faces of the knife edge discs 30 are tapered toward their peripheries as indicated at 34 at such an angle as will bring the tapered surface thereof at the end of a

sidewise movement of the arm 21 into engagement with the inner face of the associated spool flange. Due to the shallowness of the strand groove and the substantially knife edge formation of the outer discs, the strand contacts with the inner face of the head simultaneously with the outer disc affected. As the thickness of the sheave at its delivery point is substantially the same as the diameter of the wire being wound, the wire is placed snugly against the inner faces of the spool flanges at the end of each reciprocation of the head block 12 (Fig. 4).

What is claimed is:

1. In a device for feeding material in the process of being wound upon a winding spindle, a member movable in a path parallel to the winding spindle, material feeding means pivotally attached at its forward end to said member, and means for causing said means to swing upon its pivot point in a plane parallel to the axis of the spindle during the reciprocation of said member.

2. In a device for feeding material in the process of being wound upon a spool, a member movable in a path parallel to the winding surface of the spool, material feeding means pivotally attached at its forward end and at a point adjacent the winding surface of the spool to said member, and means for causing said feeding means to swing upon its pivot point in a plane parallel to the axis of the spindle during the reciprocation of said member.

3. In a device for feeding a strand in the process of being wound upon a spool, a member movable in a path parallel to the winding surface of the spool and adapted to be retracted a distance equal to the diameter of the strand at certain prescribed intervals, strand feeding means pivotally attached to said member with its delivery point in line with the winding surface of the spool, and means for causing said feeding means to swing upon its pivot point in a plane parallel to the axis of the spindle during the reciprocation of said member.

4. In a device for feeding a strand in the process of being wound on a spool, a member reciprocable in a path parallel to the winding surface of the spool, and a strand feeding means pivoting about an axis in line with the longitudinal axis of the strand as it is delivered therefrom to the spool while the member reciprocates.

5. In a device for feeding a strand in the process of being wound upon a headed spool, a member movable in a path parallel to the winding surface of the spool and adapted to be retracted a distance equal to the diameter of the wire at the end of each reciprocation thereof, an arm pivotally attached to said member, a grooved strand guiding means rotatably mounted thereon with its delivery point in line with the winding surface of the

spool, said guiding means provided at its delivery point with a thickness substantially the same as the diameter of the strand whereby the end turns of the wire are placed 5 snugly against the inner sides of the spool heads, and means for causing said arm to swing upon its pivot point during the reciprocation of said member.

6. In a device for feeding a strand in the 10 process of being wound upon a spool, a frame, a support movable thereon in a path parallel to the winding surface of the spool, a strand feeding means pivotally attached to said support, and means for causing said 15 means to swing upon its pivot point during the reciprocation of said support, said means comprising stationary members in engagement with one end and upon either side of said first mentioned means.

20 7. In a device for feeding a strand in the process of being wound upon a spool, a member movable in a path parallel to the winding surface of the spool and adapted to be retracted a distance equal to the diameter of 25 the wire at the end of each reciprocation thereof, an arm pivotally attached to said member at a point in line with the winding surface of the spool, a grooved strand guiding means rotatably mounted thereon with 30 its delivery point in line with the winding surface of the spool, said guide provided with continuous tapered surfaces upon opposite side faces terminating at the periphery in knife edges adjacent to the groove so that 35 at the end of each reciprocation of said member one of the knife edges engages the inner face of one spool head at a point removed from the point at which the wire simultaneously engages said face whereby the end 40 turns of the wire are placed snugly thereagainst, and means for causing said arm to swing upon its pivot during the reciprocation of said member.

45 8. In a device for distributing a strand in the process of being wound on a headed spool, a guide element for feeding strand material designed to be reciprocated along the longitudinal axis of the spool, comprising a composite member provided with a 50 continuous groove adjacent its circumference and having side faces provided with continuous tapered portions terminating at the periphery thereof in knife-like edges forming the side walls of the groove.

55 9. In a device for distributing a strand in the process of being wound upon a spool, an arm, one end of which is adapted to reciprocate in a path parallel to the axis of the spool, and guiding means carried by 60 said end for directing the strand to the spool, and means for restricting the movement of the other end of the arm in a direction parallel to the axis of the spool, but permitting its free movement in a path at 65 an angle thereto.

10. In a device for distributing a strand in the process of being wound upon a spool, a distributing arm, strand guiding means carried on one end thereof for guiding the strand to the winding surface of a spool, and means for restricting the other end from movement in a path parallel to the axis of the spool, but permitting the arm to bodily shift its position to permit the guiding means to travel in a path parallel to the axis of the spool. 70

11. In a device for feeding material in the process of being wound upon a spool, a member movable in a path parallel to the winding surface of the spool, material feeding means pivotally attached at its forward end to said member, and means for causing the other end of the feeding means to pivot about a movable point during the reciprocation of the member. 80

12. In a device for feeding material in the process of being wound upon a spool, a member movable in a path parallel to the winding surface of the spool, material feeding means pivotally attached at its forward end to the member, and means for causing the other end of the feeding means to successively pivot about a plurality of points distributed lengthwise along the arm as the member is reciprocated parallel to the axis 90 of the spool. 95

13. In a device for distributing a strand in the process of being wound on a headed spool, a composite guide element for feeding strand material designed to be reciprocated along the longitudinal axis of the spool, comprising circular end members, an intermediate interchangeable circular member having a diameter less than said end members and a thickness corresponding with the size of the material to be fed, and means for retaining said members in a fixed relation upon assembly, said end members tapered upon their outer faces toward their peripheries and terminating in knife-like edges which form the side walls of a groove, the bottom wall of the groove being formed by the peripheral surface of said intermediate member. 100

14. In a device for distributing a strand in the process of being wound on a headed spool, a composite guide element for feeding the strand designed to be reciprocated along the longitudinal axis of the spool, comprising an intermediate member of a thickness substantially the same as the diameter of the strand to be guided, and outer retaining members co-operating therewith to form a guideway for the strand, having a depth substantially equal to the radius of the strand. 110

15. In a device for distributing a strand in the process of being wound on a headed spool, a guide element for feeding the strand designed to be reciprocated along the longi- 120 125 130

tudinal axis of the spool, comprising an intermediate circular member having a thickness substantially the same as the diameter of the strand, and outer circular members 5 cooperating therewith and having peripheries which extend beyond the intermediate member a distance substantially equal to

the radius of the strand to provide a guide-way for the strand.

In witness whereof, I hereunto subscribe 10 my name this 27th day of September A. D., 1924.

ARTHUR HERMAN ADAMS.
